DISPENSING CONTAINER FOR SOAP
POWDER OR THE LIKE

Clara E. Lipton, New York, N. Y.

Application December 2, 1950, Serial No. 13,243

Term of patent 14 years

(Cl. D58—12.6)

To all whom it may concern:

Be it known that I, Clara E. Lipton, a citizen of the United States of America, residing at the city, county, and State of New York, have invented a new, original, and ornamental Design for Dispensing Container for Soap Powder or the like, of which the following is a specification, reference being had to the accompanying drawing, forming part thereof.

In the drawing:

Fig. 1 is a front perspective view of a dispensing container for soap powder or the like showing my new design;

Fig. 2 is a rear perspective view thereof;

Fig. 3 is a front elevational view; and

Fig. 4 is a bottom plan view.

I claim:

The ornamental design for a dispensing container for soap powder or the like, substantially as shown.

CLARA E. LIPTON.
